UNITED STATES PATENT OFFICE

LEVI CLYDE MORRIS, OF NORTH CANTON, OHIO

ELECTRIC PROGRAM CLOCK

Application filed January 21, 1929. Serial No. 334,011.

The present invention relates to improvements in electrically operated alarm clocks and has reference more particularly to a program clock for use in schools, offices and the like.

The principal object of the present invention is to provide an electric program clock wherein means is provided for automatically closing the circuit through the alarm bell for actuating the latter at any predetermined time, additional means being provided whereby the circuit closing means may be selectively positioned to close the circuit at any predetermined hour, or minute in the hour.

Still a further object is to provide an electric program clock that will at all times be positive and efficient as well as automatic in its operation for sounding the alarm at a predetermined time, or times.

Still a further object is to provide an electric program clock wherein the same includes a rotatable disc having the minute hand painted or otherwise affixed thereon, said disc being adapted for rotation through the medium of the clock train mechanism that ordinarily actuates the minute hand, said disc being provided with concentrically arranged annular series of openings for receiving a removable plug, each row of spaced openings being numbered corresponding to the hours painted on the stationary dial forming ring.

Still a further object is to provide an electric program clock of the above mentioned character that is simple in construction, inexpensive, strong and durable and further well adapted to the purpose for which it is designed.

Other objects and advantages of the invention will become apparent during the course of the following description when taken in connection with the accompanying drawings.

In the accompanying drawings wherein like reference characters indicate corresponding parts throughout the same:

Figure 1 is a front elevation of the electric program clock embodying my invention.

Figure 2 is a front elevation of the insulated base that is arranged directly behind the rotatable metallic disc, the contacts that are mounted on the front face of the insulated base being shown in elevation.

Figure 3 is a fragmentary elevational view of the rotatable disc looking at the rear side of the central portion thereof.

Figure 4 is a vertical sectional view through the casing.

Figure 5 is a detail sectional view showing the relationship of the plug with respect to one of the spring contact fingers and the stationary contact strip underlying the contact finger.

Figure 6 is a diagrammatic view of the wiring system for the present invention.

Figure 7 is a bottom plan view of the removable plug, and

Figure 8 is a fragmentary side elevation of said plug.

In the drawings wherein for the purpose of illustration is shown the preferred embodiment of my invention, the numeral 1 designates a clock case, the front side thereof being open and mounted in the open front side of the case is the ring-like member 2 having the front face thereof marked off in a manner simulating the arrangement of the hour indicating numerals of a conventional dial of a clock and this is clearly indicated in Figure 1.

Arranged for rotation within the confines of the ring-like dial 2 is the metallic disc 3. This disc is formed with twelve concentrically arranged circles of sixty holes each. The circles are marked off from one to twelve respectively, the numerals 4 gradually increasing in value from the innermost circle to the outermost one, as also more clearly disclosed in Figure 1. The holes are designated by the reference character 5, and each circle has its holes spaced one minute apart. The outermost circle is marked off at every fifth hole to indicate five minute intervals and these indicating numerals are designated by the reference character 6 also in Figure 1.

Painted on the front face of the rotatable metallic disc 3 is the minute hand 7. The mechanism for effecting the rotation of the

rotatable disc 3 will hereinafter be more fully described.

A circular contact carrying base 8 of suitable insulating material is arranged vertically within the case 1 behind the rotatable disc 3 in slight spaced relation with respect thereto, and suitable supporting brackets 9 are associated with the insulated base 8 to support the same in a stationary manner as suggested in Figure 4. This insulated base is formed with a central transverse opening to accommodate the rotatable sleeve 10 on the outer end of which is secured the disc 3 for rotation therewith. This sleeve is rotated by suitable intermeshing gearing shown generally at 11 and the gearing is in turn operated by a clock train mechanism of the conventional construction that is arranged within the housing 12 secured in the rear portion of the case 1.

The hour shaft of the clock is shown at 13 and the same extends through the sleeve 10 and carries at its outer end the hour hand 14 for movement across the front face of the perforated disc 3. Suitable gearing shown at 15 in Figure 4 provides a means whereby the clock train mechanism within the housing 12 will actuate the hour shaft 13 in the usual manner.

The front face of the insulated base 8 is formed with a substantially circular socket 16 adjacent the central opening through which extends the minute and hour shafts. A series of radially disposed spring contact segments 17 are secured at their outer ends to the bottom portion of the socket 16, the securing means 18 for each segment constituting a binding post. The inner ends of the radially disposed segments are slightly raised as more clearly disclosed in Figure 4; and the inner end of each segment is directed inwardly as at 19 for cooperation with the metallic ring 20 secured within a suitable recess provided therefor in the bottom of the socket 16 as also clearly shown in Figure 4. A binding post or terminal 21 is associated with the ring 20. Normally the resiliency of the contact segment maintains the inwardly directed portions 19 out of engagement with the contact ring 20.

A rotatable spindle 22 extends centrally within the socket 16, the inner end of the spindle being journaled for rotation within the bottom of the socket, while the outer end portion of said spindle extends through a suitable bracket 23 that is secured on the front face of the insulated base 8, as shown in Figure 2. A ratchet wheel 24 is secured on the outer end of the spindle 22 for rotation therewith, and also secured on said spindle for rotation therewith inwardly of the ratchet wheel 24 is the ring 25. A brush 26 is carried by this ring 25 for wiping engagement with the segmental contacts 17 and when the free end of this brush is in engagement with one

of said segmental contacts, the inwardly directed portion 19 of this particular contact member is held in engagement with the contact ring 20. There are twelve of these segmental contacts and their function will also be presently described.

The front face of the insulated base 8 is formed with the enlarged socket 27 that extends inwardly from the outer edge of the circular insulated base, and a contact strip 28 is arranged longitudinally within the central portion of this socket 27.

A binding post such as is shown at 29 extends through the insulated base 8 for cooperation with the contact strip 28, and one end of this contact strip is formed with a brush 30 that is at all times in engagement with the inner face of the rotatable metallic disc 3.

Extending transversely across the contact strips 28 are the spring contact fingers 31. Twelve of such fingers are provided, and the same are secured at one end at one side of the socket 27 by the terminals 32. The free ends of these spring contact fingers 31 are offset as shown at 33, and upon referring to Figure 2 it will be observed that these spring contact fingers gradually increase in length from the innermost to the outermost one. Each of the contact fingers 31 has arranged at its intermediate portion, the contact head 34 that is adapted for cooperation with the contact strip 28 and normally these contact heads are maintained out of engagement with the contact strip 28 by reason of the resiliency of the spring contact fingers 31.

Number 1 of the segmental contacts 17 is wired up with number 1 of the contact fingers 31; number 2 of the contacts 17 with number 2 of the contacts 31 and so on.

Also forming a salient part of the present invention is the metallic plug 35 that is removably fitted within any one of the openings 5 formed in the disc 3. A knurled finger engaging portion 36 is formed on the outer end of this plug while the inner end thereof is formed with the beveled portion 37 simulating the driving edge of a screw driver. The purpose of this particular construction is to provide a means whereby the alarm may be caused to ring either for a short or long period depending upon the direction in which the lower edge of the plug is disposed with respect to the contact fingers 31 that are arranged in alignment with the respective circles of holes 5.

Projecting rearwardly from the inner face of the rotatable disc 3 is the pin 38 and the free end portion of this pin is adapted to cooperate with the ratchet wheel 24 for rotating the spindle 22.

The operation of my improved electric program clock may be briefly stated as follows. The removable pin or plug 35 is placed in any one of the circles of openings or holes 5 depending upon the particular time at 130

which the alarm is to be actuated. For example the plug 35 is placed in the hole in the sixth row or circle, and in alinement with the numeral 5 this will indicate that the alarm may be actuated at five minutes past six o'clock. The brush 26 will automatically be positioned in engagement with the same segmental contact as the hour to which the hour hand 14 points, and in this instance, the hour hand is pointing to six o'clock. Hence, the segmental contact that is complementary to six o'clock will be maintained in engagement with the contact ring 20. During the rotation of the disc 3 in a clockwise direction, the plug 35 will move with the disc and will be caused to travel over the spring contact finger 31 that also is arranged in alinement with the fixed circle of a hole. As soon as the inner edge of the plug engages with the offset portion 33 of this particular spring contact finger, said contact finger will be depressed to move the contact head 34 into engagement with the contact strips 28.

This will automatically close the circuit to the bell 39 causing the alarm to be actuated, and as stated above, by positioning the lower or inner edge of the plug so that the same will be arranged longitudinally with respect to the spring contact fingers 31, then a longer ring of the bell will be had than if the inner edge of the plug is disposed transversely with respect to the spring contact fingers. As soon as the plug moves out of engagement with the adjacent contact finger 31, the circuit to the bell is again broken.

It will thus be seen from the foregoing description that I have provided an electric program clock that will at all times be positive and efficient in its operation, and furthermore the time at which the alarm is to be sounded may be selected by simply inserting the removable plug in any one of the predetermined holes formed in the disc 3. If the alarm is not to be actuated, a manual switch such as is shown at 40 and arranged in the signalling circuit may be opened.

The brush 26 moves into engagement with a new segmental contact every hour, which corresponds to the position of the hour hand. This brush is in contact with only one segment at a time.

It is to be understood that corresponding contacts of 17 and 31 must be closed before the bell will ring. Also the disk 3 and the plate or bracket 9 are in contact with the clock cast to make a ground for the other post.

The clock will carry a complete program by inserting additional plugs.

An electric program clock of this character may be placed in schools, offices, factories and the like, and due to its simplicity a clock can be constructed at a very low cost and furthermore a conventional clock train mechanism may be employed in conjunction with the present device.

While I have shown the preferred embodiment of my invention it is to be understood that minor changes in the size, shape and arrangement of parts may be resorted to without departing from the spirit of the invention and the scope of the appended claims.

Having thus described the invention, what I claim as new and desire to secure by Letters Patent is:—

1. An electric program clock comprising in combination, an insulated base, a stationary clock dial, a rotatable disc having circular rows of holes formed therein in a predetermined manner for cooperation with the dial, means for rotating the disc one complete revolution every hour, an hour hand movable across the front face of the rotatable disc, a minute hand arranged on the rotatable disc, a series of segmental contacts arranged radially within a socket formed in the front face of the insulated base, the inner end portions of the segmental contacts being raised and terminating in laterally disposed extremities, a contact ring arranged in the base with which the laterally disposed extremities are adapted to cooperate, means operable by the rotation of the disc for holding the laterally disposed extremities of the segmental contacts successively in engagement with the contact ring for one hour period, said stationary base being arranged rearwardly of the rotatable disc, a plug removably inserted in a predetermined one of the holes in said rotatable disc, and additional means arranged on the insulated base for cooperation with the aforementioned contacts to close an electric circuit to an alarm when the plug moves into position with the means.

2. An electric program clock comprising in combination, an insulated base, a stationary clock dial, a rotatable disc having circular rows of holes formed therein in a predetermined manner for cooperation with the dial, means for rotating the disc one complete revolution every hour, an hour hand movable across the front face of the rotatable disc, a minute hand arranged on the rotatable disc, a series of segmental contacts arranged radially within a socket formed in the front face of the insulated base, the inner end portions of the segmental contact being raised and terminating in laterally disposed extremities, a contact ring arranged in the base with which the laterally disposed extremities are adapted to cooperate, means operable by the rotation of the disc for holding the laterally disposed extremities of the segmental contacts successively in engagement with the contact ring for one hour period, said stationary base being arranged rearwardly of the rotatable disc, a plug removably inserted in a predetermined one of the holes in said rotatable disc, additional means arranged on the insulated base for cooperation with the aforementioned contacts to close an electric circuit.

to an alarm when the plug moves into position with the means, said means including a contact strip secured within a socket formed in the front face of the insulated base, a series of spaced contact fingers secured at one end adjacent the socket and disposed transversely across the contact strip and being normally out of engagement therewith, said spring contact fingers being arranged in alignment with the respective circular openings formed in the rotatable disc, the inner end of the plug being adapted to engage the adjacent spring contact finger to move the same into engagement with the contact strip at a predetermined time.

3. An electric program clock comprising in combination, an insulated base, a stationary clock dial, a rotatable disc having circular rows of holes formed therein in a predetermined manner for cooperation with the dial, means for rotating the disc one complete revolution every hour, an hour hand movable across the front face of the rotatable disc, a minute hand arranged on the rotatable disc, a series of segmental contacts arranged radially within a socket formed in the front face of the insulated base, the inner end portions of the segmental contact being raised and terminating in laterally disposed extremities, a contact ring arranged in the base with which the laterally disposed extremities are adapted to cooperate, means operable by the rotation of the disc for holding the laterally disposed extremities of the segmental contacts successively in engagement with the contact ring for one hour period, said stationary base being arranged rearwardly of a rotatable disk, a plug removably inserted in a predetermined one of the holes in said rotatable disc, additional means arranged on the insulated base for cooperation with the aforementioned contacts to close an electric circuit to an alarm when the plug moves into position with the means, said means including a contact strip secured within a socket formed in the front face of the insulated base, a series of spaced contact fingers secured at one end adjacent the socket and disposed transversely across the contact strip and being normally out of engagement therewith, said spring contact fingers being arranged in alignment with the respective circular openings formed in the rotatable disc, the inner end of the plug being adapted to engage the adjacent spring contact finger to move the same into engagement with the contact strip at a predetermined time, said contact fingers gradually increasing in length from the innermost one to the outermost finger.

4. In combination, a program clock including a clock mechanism, a dial, a rotatable disc operable by said clock mechanism and having concentrically arranged circular

rows of holes formed therein for cooperation with said dial, a series of segmental contact members arranged radially and rearwardly of said disc, an annular contact member, means operable by the rotation of said disc for holding said segmental contact members successively in engagement with said annular contact member for a predetermined period of time, means cooperable with said segmental contacts to close an electric circuit to an alarm, and means removably insertible in predetermined holes in said rotatable disc for cooperation with the last referred to means during rotation of said rotatable disc for closing the electrical circuit to an alarm at predetermined intervals.

5. In combination, a program clock including a clock mechanism, a dial, a rotatable disc operable by said clock mechanism and having concentrically arranged circular rows of holes formed therein for cooperation with said dial, a series of segmental contact members arranged radially and rearwardly of said disc, an annular contact member, a rotatable brush operable by the rotation of said disc for engagement with said segmental contact members for holding said segmental contact members successively in engagement with said annular contact member for a predetermined period of time, a plurality of spring contact fingers arranged in alignment with the respective circular openings formed in said rotatable disc, a contact strip, said spring contact fingers extending transversely of said strip normally out of engagement therewith, and a plug removably insertible in a predetermined one of the holes of said rotatable disc, and having its inner end adapted for engagement with the adjacent spring contact finger for moving the latter into engagement with said contact strip at a predetermined time.

In testimony whereof I affix my signature.
L. CLYDE MORRIS.
